UNITED STATES PATENT OFFICE.

WILHELM CARL HILGENDORF, OF HAMBURG, GERMANY, ASSIGNOR TO
BEECK & RIEDELL AND JOHANN MARTIN CARL MAX HARTWIG, OF
SAME PLACE.

DOOR-SECURER.

SPECIFICATION forming part of Letters Patent No. 534,716, dated February 26, 1895.

Application filed November 5, 1894. Serial No. 527,891. (No model.) Patented in Germany April 26, 1893, No. 74,853.

To all whom it may concern:

Be it known that I, WILHELM CARL HILGENDORF, a subject of the German Emperor, and a resident of Hamburg, in the German Empire, have invented certain new and useful Improvements in Automatic Door-Securers, (for which I have obtained a patent in Germany, No. 74,853, dated April 26, 1893,) of which the following is a specification.

10 My invention has relation to that class of door checks whereby a door may be partially opened but not sufficiently to admit of the passage of a person.

The invention has for its object the provision of means whereby the construction of this class of devices is not only simplified, but whereby the tampering with the door check from without is more effectually prevented and the disengaging of the locking devices of the check from within facilitated, as will now be fully described, reference being had to the accompanying drawings, in which—

Figure 1 is a face view of the door check, the door being closed, and Figs. 2 and 3 are horizontal sections through parts of a door frame or jamb, and a door through the door check, Fig. 2 illustrating the operative devices of the check in the position they occupy when the door is closed, and in dotted lines 25 the position they occupy when said door is opened to the full extent permitted by the check, while Fig. 3 shows said operative devices in the position they occupy on opening the door when said devices are not intended 30 to operate as a check.

In the above figures of the drawings *a* indicates the door, to which is secured by means of screws the check latch plate *e*, from the forward end of which projects the check latch 35 *e'* terminating at its outer end in a cross or T-head, said check latch, as shown in Figs. 2 and 3 curving upwardly and forwardly from its plate so as to leave a certain space between its head and the door *a*, or the door frame or 40 jamb *b*. To the latter is secured the locking device, which consists of a hasp constructed in the form of a bell-crank lever, fulcrumed at *d* in ears formed on a bracket *c*, secured to the door frame by means of screws. The

short arm *d*² of the hasp terminates preferably in a cross head *d*⁴ that serves as an abutment or bearing for the T-head of the check latch *e*, when the door is closed, as shown in Figs. 1 and 2. The long arm *d*³ of the bell crank lever is slotted longitudinally, as shown at *d*⁶, the inner end of the slot being suitably enlarged to admit of the passage therethrough of the T-head of the check latch, as shown at *d*⁷, and said longer slotted arm of the lever constitutes the check hasp. From the inner 55 end of the narrower portion of the longitudinal slot *d*⁶ of the hasp *d*³ project downwardly curved tongues *d*⁸ one on each side of said slot, the outer ends of said tongues lying on opposite sides of the check latch immediately 60 behind its T-head so that on opening the door, the latch will ride over the tongues, and is thereby guided into the enlarged portion *d*⁷ of the slot *d*⁶ and thence into the more contracted portion, so that said door can be 65 opened until the T-head of the latch reaches the outer end of the hasp slot, as shown in dotted lines in Fig. 2.

In practice I prefer to employ a stop *f* proximate to the lever fulcrum for the purpose of 70 limiting the movement of said lever toward the door frame, as shown in Fig. 2.

It is obvious that by the means described it is impossible to disengage the check latch from its hasp or keeper from without the door 75 when the latter is partially open without applying destructive force, the parts resuming their normal position when the door is shut again. If it is desired to admit passage through the door, the person within the room 80 simply swings the check hasp toward the door frame, having previously manipulated the door latch so that the door will open under the action of the short arm *d*² of the check latch, as shown in Fig. 3.

If it is desired to maintain the check out of 85 operation the pin *f* is withdrawn and the hasp swung back into the position shown in dotted lines in Fig. 3, when the pin is again inserted in its bearings in the bracket *c* and between 90 the long and short arms of the hasp. It is obvious therefore, that the operation of the check is controlled by the movements of the

check latch, while the free movements of the door are dependent upon the movements of the check hasp.

Having thus described my invention, what 5 I claim as new therein, and desire to secure by Letters Patent, is—

1. In a door check, a bell crank lever to be fulcrumed to a door frame and having arms of unequal length, in combination with a 10 check latch to be rigidly secured to a door, said latch adapted when moved in one direction to interlock with and slide along the longer arm of and turn the lever in said direction, and when moved in a reverse direction 15 to slide along and release said longer arm and act upon the shorter arm of such lever

and turn the same in said reverse direction, for the purpose set forth.

2. In a check latch of the class described, the combination with the bell crank lever d^2 20 d^3 and its fulcrum bracket provided with bearings in rear of the lever fulcrum bearings, of a pin f removably seated in its said bracket bearings, for the purpose set forth.

In testimony that I claim the foregoing as 25 my invention I have signed my name, in presence of two witnesses, this 22d day of October, 1894.

WILHELM CARL HILLGENDORF.
